UNITED STATES PATENT OFFICE.

GUSTAVE BJORKLAND, OF BAYONNE, NEW JERSEY

ACTION FOR GRAND PIANOS.

1,100,283.

Specification of Letters Patent. Patented June 16, 1914.

Application filed October 25, 1913. Serial No. 797,158.

To all whom it may concern:

Be it known that I, GUSTAVE BJORKLAND, a citizen of the United States, residing at Bayonne, county of Hudson, and State of New Jersey, have invented a new and useful Improved Action for Grand Pianos, of which the following is a specification.

This invention relates to an action for grand pianos, which may be operated either by keys or by a self playing device, and which is so constructed that the player mechanism operates upon the action entirely independent of the keys, so that while the piano is played automatically the keys remain inert and functionless.

In the accompanying drawing: Figure 1 is a side view partly in section of a piano action embodying my invention, showing the normal position of the parts; Fig. 2 a similar view with the key depressed, and Fig. 3 a detail of the rocker and adjoining parts.

To a flange 10 of the action rail 11, is fulcrumed the support 12, from which extends upwardly a flange 13, to which is pivoted the repetition lever 14. The jack 15 which is pivoted to the support, passes through a slot of lever 14, and engages the hammer butt 16 all as usual. As heretofore generally constructed, the support 12, was directly engaged by and actuated from the capstan 17 extending upwardly from the key 18. I discard this arrangement, and interpose between the capstan and support an additional lever or member 19, which is entirely disconnected from the key and support, and is adapted to be actuated either by the key or by pneumatic or other automatic means. This additional member is pivoted at its forward end to a flange 20 of a fixed rail 21, which is located a substantial distance above the key. The rear or free end of the lever extends some distance back of the key and beneath the flange 10 of support 12, the key being made shorter than in actions as heretofore generally constructed.

This free end is engaged from below by the sticker 22 of a pneumatic or other self-playing mechanism, such sticker extending upwardly back of the key so as to clear the same. At its top the lever carries the back check 23, and a pad 24 by means of which it is adapted to actuate the damper-lever (not shown). At a point opposite the capstan 17, the member 19 is provided with an integral projection 25, having a slightly slop-

ing top upon which rests a knuckle 26 of support 12, so that the lever actuates the latter, with a minimum amount of friction. Means are provided for transmitting the movement of the key 18 to the lever in such a manner that friction between the latter and capstan 17 is likewise prevented, such means being especially desirable as these two parts turn with different radii on widely different centers. These means consist of a rocker or movable block 27 received within a lower notch 28 of the lever and provided with an upwardly extending flange 29, that enters a recess 30 above said notch. A pivot 31, secures flange 29 to the cheeks of recess 30, so that the rocker is freely movable relatively to the lever within notch 28. The lower face of rocker 27 is rounded and cushioned as shown to form a contact surface for the head of capstan 17 upon which the rocker is thus movably supported.

When the instrument is played by hand, the movement of the key will be transmitted from the capstan through the rocker to the lever and thence to the support 12, from whence the conventional part of the action is operated in the usual manner. During this operation, the rocker will turn freely on its fulcrum 31, while the support will rock freely on projection 25, so that friction is avoided.

When the instrument is played automatically, the movement is imparted from the sticker 22 directly to the lever, without in any way burdening or requiring the intervention of the key. In this way power is economized while furthermore the key may be locked against movement by a rail 32. To regulate the stroke of the action, while being played either manually or mechanically, there is tapped into a flange of the action rail 11 a regulating button 33, which limits the sweep of the lever.

I claim:

1. In a grand piano action, a key having a capstan, a rail above the key, a lever pivoted to said rail and extending a distance beyond the key, a support resting upon the lever, an automatically actuated lifter engaging the projecting end of the lever, and a rocker pivoted to the lever and resting upon the capstan.

2. In a grand piano action, a key having a capstan, a rail above the key, a lever pivoted to said rail and extending a distance beyond the key, said lever being provided with

a lower notch, a support resting upon the lever, an automatically actuated lifter engaging the projecting end of the lever, and a rocker pivoted to the lever and accommodated within the lever-notch, said rocker being movably supported on the capstan.

3. In a grand piano action, a key having a capstan, a rail above the key, a lever pivoted to said rail and having an upper projection and a lower notch, said lever extending a distance beyond the key, an automatically actuated lifter engaging the projecting end

of the lever, a second rail above the projecting end of the lever, a support pivoted to said second rail and having a knuckle that rests upon the lever-projection, and a rocker pivoted to the lever and accommodated within the lever-notch, said rocker being movably supported upon the capstan. 15

GUSTAVE BJORKLAND.
